UNITED STATES PATENT OFFICE

JOHN P. JOHNS, OF NEW YORK, N. Y.

MARKER LAMP

Application filed April 27, 1929. Serial No. 358,710.

This invention relates to marker lamps of the type that are used as markers on the rear end of trains and its objects are to provide a lamp as a marker that may be lighted by oil or by electric current; more specifically, the invention relates to an adapter that may be applied to existing oil lamps so that they may be illuminated either by oil or by electricity.

10 Marker lamps of the type to which this invention applies are provided with four lenses giving indications in four directions and, for the sake of reliability, they must be usable as isolated units lighted by oil. 15 The oil fount has a capacity of about 50 hours and occupies a considerable portion of the base of the lamp. The flame is arranged to centre in the focal point of the lenses.

20 Most of the modern railway coaches are equipped with electric lighting and when electric current is available, the marker lamps may be illuminated by an electric bulb which can be connected to a convenient 25 outlet. The electric illumination of marker lamps has a number of advantages over the oil system. The source of illumination can be centered more accurately in the focus of the lenses, a stronger and more pronounced 30 light beam is obtained and greater convenience obtains with its use.

In case the electric supply should fail, safety demands that an oil light be available and the present practice is to use an 35 oil marker light and a separate electric marker lamp. These lights are removed at the end of the journey and the labor of removing and replacing them is doubled when separate oil and marker lamps are used.

40 It is the purpose of this invention to adapt existing oil burning lamps to use an electric bulb when an electric supply is available, but to be instantly convertible for use with oil when the electric supply fails. This 45 result is obtained by an adapter secured within the lamp housing as a permanent fixture, but out of the way of the flame when the oil burner is in use, even when the housing is tilted from the vertical. To 50 change over from oil to electric lighting, the

oil burner is removed from the fount and an electric bulb is screwed into the adapter, the lamp having been previously plugged into the lighting mains of the car. By reversing this process and removing the bulb and replacing the burner, the lamp is ready for use with oil.

Owing to the lens apertures in the walls of the lamp housing, the adapter has to be specially formed to fit between a pair of apertures so as not to obscure the light or cast a shadow in the indication from any of the lenses. Also, it is necessary to provide a certain amount of adjustment in the location of the socket so as to bring the lamp bulb filament into the approximate focus of the lenses.

In the drawings, a standard marker lamp is illustrated in elevation in Fig. 1, with the door open; a plan view of this lamp with the cover removed and with an electric bulb in place is shown in Fig. 2; Fig. 3 shows the relation of the adapter to the lens apertures of the housing; Fig. 4 is a detail, partly sectioned, showing the method of attaching the adapter to the housing; and, Fig. 5 is another detail, partly sectioned, showing the attachment of the adapter to the housing.

The marker lamp housing is indicated by 11, the base by 12 and the cover by 13. The indications are given by the lenses 14, 15, 16 and 17 located at right angles to each other as shown and having a common focal point at α in the centre of the housing. The door 18 engages the vertical guides at 19 whereby the door may be slid open or shut.

The oil fount 20 rests on the base 12 and is held in position by the cleats 21 but may be slid out of the housing for trimming purposes. The oil burner at 22 is of the usual type and terminates in the flame 23 at the focal point α .

The adapter 25 may be made from moulded material and is secured to the housing by means hereinafter referred to. The socket 25 is formed integral with 25 and centres on the axial line of the lenses $a-b$ and is disposed with its centre pointing towards the focal point α . Terminals 27 may

be provided in 25 by which the electrical connections are made to the socket from the lighting circuit of the car. When the lamp bulb 28 is screwed into the socket 26, the filament is located at the focal point *a* where it is most effective in producing a strong beam of light.

It is apparent that the lamp bulb intercepts the position of the oil burner so that they cannot both be in the operative position at the same time. When the bulb is in use the burner is removed and when the burner is in use the bulb is removed. The bulb is the regular lighting bulb of the car and is easily replaced.

When these lamps are removed they are carried by the bail 42 pivotally secured by lugs 41 to the housing and usually two or more lamps are carried in one hand so that the housing is tilted from the vertical as indicated by line *d*. This brings the lamp flame and the fumes therefrom towards the lamp socket 26 which is a fixture of the housing. For this reason the lamp socket is placed on the line of the flame where the fumes pass over it when the housing is tilted as described, or in rounding a curve on the track. This is an important feature of the invention, as attempts to place the lamp socket in the head of the housing have not been satisfactory owing to the fumes from the burner affecting the socket and its electrical connections. It will be observed that the large oil fount prevents the socket of the bulb being placed in the base of the housing.

The drawing in Fig. 3 shows the developed relation of the adapter to the lens apertures of the housing. The wall of the housing at *b* and *c* is comparatively narrow and the adapter is accordingly narrowed and curved as indicated to conform to the contour of the lens openings.

The upper part of the adapter is somewhat triangular in shape and is secured to the housing by three screws 31, 32 and 33, entering slotted holes as indicated at 36, Fig. 5 which are covered by the washers 35. The spherical projection 34 is formed on 25 in the centre of the triangle formed by the screws 31, 32 and 33 and this projection rests upon the curved wall of the housing as indicated in Fig. 4. It will be observed from this figure that the bracket 25, is spaced from the housing 11, the ball 34 being the only part engaging the housing. It is apparent that by adjusting the screws 31, 32 and 33, the bracket 25 will rotate upon the ball 34 and thereby a universal adjustment of the position of the bulb filament may be obtained. The slots 36 aid in securing this adjustment vertically.

This adapter is made as a unitary construction to be applied to existing marker lamps using oil burners. It is compara-

tively inexpensive to make and easy to apply.

Having thus described my invention, I claim:

1. In combination, a marker lamp as described including a housing having a plurality of lenses at right angles to each other giving indications in different directions, an oil fount in the base of said housing with a removable oil burner and a wick located to produce a flame at the focal point of said lenses; an adapter for an electric light bulb comprising a depending bracket opposite the wall of said housing between a pair of said lenses and not exceeding the width of said wall adjustably secured with a ball engagement to said housing above the plane of said lenses and having a horizontal socket adjacent the wall of said housing between the apertures for a pair of said lenses, said socket arranged to support a light bulb with its filament at the focal point of said lenses, said light bulb being interchangeable with said oil burner for illuminating said lamp.

2. In a marker lamp as described, the combination, a housing having four lenses placed at right angles to each other and having a common focal point, an adapter for securing an electric light bulb with its filament at the focal point of said lenses, said adapter comprising a bracket secured to said housing above the plane of said lenses by three screws spaced in the form of a triangle and a spherical projection integral with said bracket centered between said screws engaging the concave side of the curved wall of said housing and an extension on said bracket opposite the wall between a pair of said lenses and substantially the width of said wall supporting a horizontal socket with its centre on the same plane as the axis of said lenses for supporting said bulb.

In testimony whereof I affix my signature.

JOHN P. JOHNS.
